CONCRETE HOPPER VALVE MEASURING DEVICE

Filed July 12, 1927

INVENTOR.

Oscar W. Phifer

BY

C. G. Charles

ATTORNEY.

UNITED STATES PATENT OFFICE

OSCAR W. PHIFER, OF TOPEKA, KANSAS

CONCRETE HOPPER VALVE MEASURING DEVICE

Application filed July 12, 1927. Serial No. 205,264.

My invention relates to a concrete hopper valve measuring device.

The object of my invention is to provide a hopper having a rockable partition and a choke member to control the flow of concrete.

A further object of my invention is to provide a valve measuring means for the lower end of the hopper.

A still further object of my invention is to provide a valve measuring means having a cutoff for the measurer and a cutoff for the hopper when the measuring device is drawn forward to discharge its contents into a mould or form.

These and other objects will hereinafter be more fully explained.

Referring to the drawing in which like characters apply to like parts in the different views:

Fig. 1 is a perspective view of the hopper and valves with parts removed for the purpose of illustration.

Fig. 2 is a side view of one of the catches for the partition plate.

Fig. 3 is a plan view of the detent shown in Fig. 2.

Fig. 4 is an end view of the choke plate showing the adjusting screw.

A container 1, open at the top and bottom is slidably positioned between a plate 2 and the lower end of a hopper 3. A cutoff board

4 is integral with the upper portion of the container and slidably engages with the guides 4' as shown. This board serves to close the bottom of the hopper when the container is moved over the aperture at A in the plate 2 to discharge its contents.

Arms 5 are pivotally connected between the levers 6 and the container 1. When the levers 6 are rotated in the direction of the arrow at B in Fig. 1 the container moves over the aperture A and the cutoff board 4 closes the bottom of the hopper. The container may be divided by a partition placed as indicated by the dotted lines at C in Fig. 1 when only half is needed.

A choke plate 7 is hinged across and near the lower end of the hopper 3. A screw 8 is arranged to adjust the position of the choke plate as illustrated in Fig. 4. The purpose

of the choke plate is to reduce the discharge opening of the hopper as desired.

A partition plate 9 is pivotally connected at its lower end to near the mouth of the hopper at D. This plate fits rather closely at its edges to the sides of the hopper and may be held in a vertical position by catches 9' fastened to the front and rear sides of the hopper as at E.

These catches protrude through the apertures 10 in the sides of the hopper and are fastened to the said sides by the spring members 11.

When the catches 9 are pulled back as indicated by the arrow at F in Fig. 2, the partition plate may be positioned to either side of the hopper as indicated by the dotted lines G in Fig. 1. Such a position is used when a partition is placed in the container 1 at C and only one side of the said container is to be filled with concrete.

The lower portion of the plate 9 is removed adjacent the choke plate 7 to allow free movement of both plates. A V-shaped flap 12 is hinged to the plate 9 at this point and functions to close the opening between the said plates.

By proper positioning of the plates 7 and 9 the discharge of concrete from the hopper into the container may be controlled as desired.

Such modifications may be employed as lie within the scope of the appended claims.

What I claim as new and desire to secure by Letters Patent is:

1. In a dispensing hopper for concrete, a hopper having a spout rectangular in cross section, hinged gates positioned at the lower extremity of the hopper, one of the hinged gates being pivoted at the center and extreme bottom of the spout and rockable to the sides thereof and means to position the said gate in the center of the spout, a hinged flap on the said hinged gate in continuous contact with a second hinged gate, the second hinged gate being positioned somewhat above the discharge point of the spout and adjustable to the first said hinged gate and functioning to vary the discharge aperture of the spout,

means to position the second hinged gate substantially as shown.

2. In a dispensing hopper for concrete, in combination a hopper, valves in the hopper, said valves comprising a vertical plate pivotally connected at its lower part to near the discharge point of the hopper, a choke plate pivotally connected to the side of the hopper at right angles to the vertical plate and a container slidably positioned to the bottom of the hopper, a cut off board integral with the said container and functioning to close the hopper when the said container is moved.

In testimony whereof I affix my signature.

OSCAR W. PHIFER.
